[57] CLAIM

The ornamental design for a cigarette package display rack, as shown.

DESCRIPTION

FIG. 1 is an enlarged perspective view of a cigarette package display rack showing my new design;

FIG. 2 is a front elevational view thereof;

FIG. 3 is a side elevational view taken from the left of FIG. 1, the side opposite being a mirror image thereof;

FIG. 4 is a rear elevational view thereof.

FIG. 1.
